United States Patent Office

Des. 204,780
Patented May 17, 1966

204,780

DRINKING CUP OR SIMILAR ARTICLE

Paul K. Schilling, St. Paul, Minn., assignor to Plastics, Inc., St. Paul, Minn., a corporation of Minnesota

Filed June 8, 1965, Ser. No. 85,620

Term of patent 14 years

(Cl. D44—9)

FIG. 1

FIG. 2

FIG. 3

FIG. 4

FIGURE 1 is a perspective view of a drinking cup or similar article, showing my new design,

FIGURE 2 is a top plan view of the same,

FIGURE 3 is a side elevation of the cup, and

FIGURE 4 is an end elevational view of the handled end of the drinking cup.

The characteristic feature of my design resides in the handle as shown.

I claim:

The ornamental design for a drinking cup or similar article, as shown and described.
